CONTROL FOR TRAFFIC SIGNAL SYSTEMS

Samuel S. Stelp and Frank H. Richterkessing,
Louisville, Ky., assignors to Nachod & United
States Signal Company, Inc., Louisville, Ky.

Application August 25, 1928, Serial No. 302,020

17 Claims. (Cl. 177—337)

Our invention relates to the control of electrically-operated traffic signals primarily intended for use at the intersection of thoroughfares.

The main object of our invention is to provide means wherein an electric car approaching the intersection will take control of the traffic signal to prolong a proceed indication to favor the preferential movement of the car. In other words, the traffic signal will be displaying "stop" and "proceed" indications periodically until a car enters a certain predetermined zone with respect to the intersection, wherein the periodic control of the traffic signal indications will be interrupted, and the display of the "proceed" indication on the electric line and the "stop" indication for the intersecting traffic prolonged to permit a continuous movement of the car past the intersection. The system is so arranged that the periodic control is restored after the car passes the intersection, and when the automatic timer has entered the period for displaying the "proceed" indication on the E—W electric line.

It will be apparent to those skilled in the art that, since the system does not interrupt the signal periods regulated by the automatic, motor-driven time-element of the traffic signal control, the system is readily adaptable to the so called wave or platoon system which, at the present time, is extensively used throughout the country.

Our invention resides in a new and novel combination, construction and relation of various electrically operated switches, circuits and other parts hereinafter more fully described and disclosed in the drawing.

In the drawing accompanying our specification:

Fig. 1 is a schematic circuit diagram disclosing the general principles employed in our system.

Fig. 2 is a graphic representation of a series of signal units operating synchronously.

Our invention is intended primarily to be controlled by cars which are supplied with operating current by means of an overhead trolley wheel or current collector, represented in Fig. 1 by W₁ or W₂, although it may be controlled by vehicles operated by other methods.

In the system shown in Fig. 1, the letter D designates a trolley wire or conductor for west-bound car movements. Positioned adjacent this trolley wire D, are trolley contactors 3W and 5W, which contactors are normally insulated therefrom, but electrically connected thereto, when the current collector W₂ engages the trolley contactors 3W and 5W respectively. The characters

D₁ designate a trolley wire or conductor for east-bound car movements. Positioned adjacent this trolley wire D₁, are trolley contactors 3E and 5E, which contactors are normally insulated therefrom, but electrically connected thereto, when the current collector W₁ engages the trolley contactors 3E and 5E respectively.

At the intersection, the characters TS designate a traffic signal, which signal periodically displays "stop," "caution" and "proceed" indications for the E—W electric line traffic and the N—S intersecting traffic.

We also employ electrically operated relays R and R₁ that are under the control of current collectors engaging the respective trolley contactors. Relay R is provided with two operating coils A and C, and a contact plunger R. The plunger P is provided with a contact ring A₂ that normally engages contacts 28 and 29, and is brought into this position by the energization of the coil C. When the coil A is energized the contact plunger P is shifted, and the contact ring A₂ is brought into contact engagement with contacts 68 and 69 and out of contact engagement with contacts 28 and 29. Relay R₁ is provided with two operating coils A₁ and C₁, and a contact plunger P₁. The plunger P₁ is provided with a contact ring A₃ that normally engages contacts 62 and 63 and is brought into this position by the energization of the coil C₁. When the coil A₁ is energized the contact plunger P₁ is shifted, and the contact ring A₃ is brought into contact engagement with contacts 31 and 32 and out of contact engagement with the contacts 62 and 63.

We also employ an electrically operated relay R₂, which relay is controlled by a circuit established thru the relays R and R₁ respectively, and certain auxiliary circuits controlled by the motor-driven time-element device controlling the display of the traffic signal indications. The relay R₂ is provided with an operating coil L and two contact bridging bars A₄ and A₅, which bridging bars are insulated from each other. The coil L of relay R₂ is normally deenergized, and the contact bridging bars A₄ and A₅ normally engage their respective back contacts 40—41 and 56—57. When the coil L is energized, the contact bridging bars A₄ and A₅ are raised, and removed from contact engagement with their respective back contacts, and brought into contact engagement with their respective front contacts 12—95 and 52—53.

We also employ a motor-driven time-element device for periodically and cyclically displaying

"stop," "caution" and "proceed" signals. The letter M designates a motor that rotates cam segments C2, C3, C4 and C5, which segments are mounted on a common shaft 96. With reference 5 to Figure 1, it will be observed that the rotation of the cam segments in the direction of arrow 97 provides a cyclical opening and closing of various contacts, which contacts control circuits connecting the signal indications.

10 The outline figure TS is a symbolic representation of a traffic signal comprising three decks of signal indications displaying in four directions. In the upper deck, red lenses 81 and 82 face N and S on the intersection, and green lenses 15 83 and 84 face W and E on the electric line, and these have a common light source designated by L1. In the center deck, four lenses 85, 86, 87, and 88 display an amber or caution indication, and each is provided with an independent light 20 source, lens 85 having a light source designated by L4, lens 86 having a light source designated by L5, lens 87 having a light source designated by L2, and lens 88 having a light source designated by L3. The caution indications are not 25 displayed simultaneously, but are displayed at intervals that will be fully described later in the description. In the lower deck, green lenses 89 and 90 face N and S on the intersection, and red lenses 91 and 92 face W and E on the electric 30 line, and these have a common light source designated by L6. For clarity of the description each of the three decks are shown in a plan view, and this must be taken into consideration 35 when the description is read, so that the display of the signal indications will be understood properly.

The indications of the traffic signal are normally displayed cyclically; that is, each indication displays a certain predetermined time before 40 a display of another signal indication occurs, all of which occurs in a definite sequence of a predetermined cycle. Starting for instance at an arbitrarily selected time of the cycle, we have a display of a green signal in both directions for 45 the W and E electric line traffic, and a red signal in both directions for the N and S intersecting traffic. The circuit for these indications is completed from the positive side of the line BX, thru wire 7, wire 13, contact arm 14 of the motor-driven time-element, contact 15, contact 16, thru 50 the stationary contact arm 17, wire 18, wire 19, wire 20, wire 21 to the signal lamp L1, which lamp is a common light source for the four indications, wire 79, wire 2, wire 1 to the common 55 return of the line CX. With reference to Figure 1, it will be observed that these indications will display as long as cam segment C2 retains contacts 15 and 16 engaged, which is for one half of the total cycle. It will also be observed that 60 just as the cam segment C2 nears the end of its period, cam C3 actuates contact arm 23, which actuation brings contacts 24 and 25 into contact engagement, and an amber caution signal is displayed to warn the east and west bound traffic 65 that a change is about to be made in the display of the signal indications. As previously mentioned, the caution indications are not displayed simultaneously to all traffic, but only to the traffic receiving the proceed indication. The circuit 70 for the E-W caution indication is completed from the positive side of the line BX, thru wire 7, wire 8, wire 22, contact arm 23 of the motor-driven time-element, contact 24, contact 25 thru the stationary contact arm 26, wire 27, contact 28 75 of relay R, contact ring A2, contact 29, wire 30,

contact 62 of relay R1, contact ring A3, contact 63, wire 64, wire 66, to the lamp L2, which lamp is the light source for lens 87 facing the W electric line traffic. It will be noted that wire 64 connects two branch circuits, one connection to wire 66 as described, and the other to wire 65 which feeds the light source for the lens facing the E electric line traffic. The circuit for the latter is completed from wire 64 to the branch wire 65, thru wire 65 to the lamp L3, which lamp is the 10 light source for lens 88 facing the E electric line traffic. Both lamps L2 and L3 have a common connection to the common return thru wire 89, wire 3, wire 2, wire 1, to the common return of the line CX. Cams C2 and C3 disengage their 15 respective contact arms simultaneously, and instant to this operation, cam C5 actuates contact arm 46, which actuation brings contacts 47 and 48 into contact engagement. These operations extinguished the former indications, and displayed a red indication for the E-W electric line traffic and a green indication for the N-S intersecting traffic. The circuit for the E-W red and N-S green indications is completed from the positive side of the line BX, thru wire 1, wire 8, wire 9, wire 10, wire 45, contact arm 46 of the motor-driven time-element, contact 47, contact 48, thru the stationary contact arm 49, wire 50, wire 55, contact 56 of relay R2, contact 20 bridging bar A5, contact 57, wire 58 to the signal 30 lamp L6, which lamp is the common light source for the four indications, wire 4, wire 3, wire 2, wire 1, to the common return of the line CX. With reference to Figure 1 it will be observed that these indications will display as long as cam segment C5 retains contacts 47 and 48 engaged, which is one-half of the total cycle. It 35 will also be observed that just as the cam segment C5 nears the end of its period, cam C4 actuates contact arm 35, which actuation brings contacts 36 and 37 into contact engagement, and an amber caution indication is displayed to warn the N-S intersecting traffic that a change is 40 about to be made in the display of the signal indications. As previously mentioned, the caution 45 indications are not displayed simultaneously to all traffic, but only to the traffic receiving the proceed indication. The circuit for the N-S caution indication is completed from the positive side of the line BX, thru wire 7, wire 8, wire 9, wire 34, contact arm 35 of the motor-driven 50 time-element, contact 36, contact 37, through the stationary contact arm 38, wire 39, contact 40 of relay R2, contact bridging bar A4, contact 41, wire 42, wire 44 to lamp L5, which lamp is the 55 light source for the lens 86 facing the S intersecting traffic. It will be noted that wire 42 connects two branch circuits, one connection to wire 44 as described, and the other to wire 43 which feeds the light source for the lens facing the N intersecting traffic. The circuit for the latter is completed from the wire 42 to the branch wire 43, thru wire 43 to the lamp L4, which lamp is the light source for the lens 85 facing the N intersecting traffic. Both lamps L4 and L5 have a common connection to the common return thru wire 80, feeding to wire 3, thru the wire 3, wire 2, wire 1, to the common return of the line CX. Cams C4 and C5 disengage their 60 respective contact arms simultaneously, and instant to this operation cam C2 actuates contact arm 14, and the cyclic display of the signal indications is repeated.

In the description of the car control of the traffic signal indications, we will first take into 70 75

consideration a single car movement eastbound. When the current collector W1 engages the trolley contactor 3E, coil A of relay R is energized, thereby shifting plunger P of relay R and bringing contact ring A2 into contact engagement with contacts 68 and 69 and out of contact engagement with contacts 28 and 29. The circuit for the energization of coil A is completed from the trolley wire D1, thru the current collector 5 W1, thru the contact strips of the trolley contactor 3E, wire 75, coil A of relay R, wire 71, to ground G. As soon as the current collector disengages the trolley contactor, the coil A of relay R is deenergized, but the plunger P remains in its shifted position. The shifting of plunger P opened the circuit of the E-W caution indication, normally completed through contacts 28 and 29, and closed a circuit through contacts 68 and 69. This operation will not affect the display of the signal indications, unless the signal was displaying the E-W caution indication, or not until the timer passes thru the necessary cycle to establish this circuit. After the automatic, motor-driven time-element device passes 20 thru the necessary cycle to provide a display of a green indication for the E-W electric line traffic and a display of a red signal indication for the N-S intersecting traffic, the coil L of relay R2 is energized. The circuit for the energization of coil L is completed from the positive side of the line BX, thru wire 7, wire 13, contact arm 14 of the motor-driven time-element, contact 15, contact 16, thru the stationary contact arm 17, wire 18, wire 70, contact 69 of relay R, contact ring A2, contact 68, wire 67, wire 60, wire 59, coil L of relay R2, wire 94, wire 1 to the common return of the line CX. The energization of the coil L of relay R2 raised the contact bridging bars A4 and A5 out of engagement 30 with their respective back contacts and brought them into contact engagement with their respective front contacts, as hereinbefore described.

Since the aforesaid circuit is completed through contacts 15-16 controlled by cam C2 and the contacts 68-69 of relay R, it will be apparent that the coil L of relay R2 will not become energized, unless relay R is operated by coil A thereof, and not until the cam C2 closes contacts 15-16.

As previously described, cam C3 actuates contact arm 23 and brings contacts 24-25 into engagement shortly before the cam C2 nears the end of its time of engagement with contact arm 14. However, with relay R operated by coil A, the contacts 23-29 are disengaged, and the E-W caution indication will not display.

As hereinbefore described, cam C5 actuates contact arm 46, and brings contacts 47 and 48 into contact engagement, as soon as cams C2 and C3 disengage their respective contact arms. It will be observed that contacts 47 and 48 normally control the circuit for the E-W red and N-S green indications, but since the contact bridging bar A5 of relay R2 is out of contact engagement with its back contacts 56 and 57, this signal circuit is open, and the indications are not displayed. The opening of contacts 15 and 16, which contacts are controlled by cam C2, opened the pickup circuit of coil L of relay R2, but the 50 coil remained energized by reason of a stick circuit completed through front contacts 12-95 of relay R2. Likewise, the E-W green and N-S red indications, continued to display by reason of a circuit completed through contacts 12-95 60 of relay R2. The stick circuit for the coil L of

relay R2 is completed from the positive side of the line BX thru wire 7, wire 8, wire 9, wire 10, wire 11, front contact 12 of relay R2, contact bridging bar A4, front contact 95, wire 93, wire 20, wire 19, wire 70, contact 69 of relay R, 5 contact ring A2, contact 68, wire 67, wire 60, wire 59, coil L of relay R2, wire 94, wire 1, to the common return of the line CX. The circuit for continuing the display of the E-W green and the N-S red indications is completed from the positive side of the line BX thru wire 7, wire 8, wire 9, wire 10, wire 11, front contact 12 of relay R2, contact bridging bar A4, front contact 95, wire 93, wire 21 to the signal lamp L1, which lamp is the light source for the four indications, 15 wire 79, wire 2, wire 1, to the common return of the line CX. It can be seen that as long as the coil L of relay R2 remains energized, the E-W green and the N-S red indications, will continue to display as hereinbefore described. 20

As soon as the trolley car passes the intersection, the current collector W1 engages trolley contactor 5E, and the coil C of relay R is energized. The circuit for energizing coil C is completed from the trolley wire D1, through the contact strip of the trolley contactor 5E, wire 76, coil C of relay R, wire 72, to the ground G. The energization of the coil C restores relay R to normal. Restoring relay R to normal opens the pick-up 30 and stick circuits for relay R2 completed through contacts 68 and 69 of relay R. However, if the automatic, motor-driven timer has entered the period for displaying the E-W red and N-S green indications, the coil L of relay R2 will not 35 be de-energized, as a holding circuit is established through contacts 47 and 48 of the motor-driven time-element, to retain the coil L of relay R2 energized, and thus continue the display of the E-W green and N-S red indications until 40 the automatic, motor-driven timer enters the period for displaying the E-W green and N-S red indications, wherein the periodic control is restored to the automatic, motor-driven timer. The aforesaid holding circuit for coil L is completed from the positive side of the line BX thru wire 7, wire 8, wire 9, wire 10, wire 45, contact arm 46 of the motor driven time element, contact 47, contact 48, thru the stationary contact arm 49, wire 50, wire 51, front contact 50 52 of relay R2, contact bridging bar A5, contact 53, wire 54, wire 59, coil L of relay R2, wire 94, wire 1 to the common return of the line CX. As long as the coil L of relay R2 remains energized by reason of the latter mentioned holding 55 circuit, the E-W green and N-S red indications will continue to display as hereinbefore described. As cam C5 approaches the end of its time of engagement with the contact arm 46, cam C4 embraces the contact arm 35 and brings contacts 36 and 37 into contact engagement. However, no caution signal circuit is established, as this circuit is open by reason of the bridging bar A4 of relay R2 being out of engagement 60 with its back contacts 40 and 41. As soon as the cam C5 disengages the contact arm 46, the holding circuit for the coil L of relay R2 is opened and the contact bars A4 and A5 are restored to normal. Restoring contact bridging bars A4 and A5 to normal, results in the entire system being restored to normal, and under the sole influence of the motor driven time element. It will be noted, however, that the green W-E electric line indication and the red N-S intersecting traffic indication continued to display 70 75

even after the car has passed the intersection. This display is under the influence of the cam C2 of the motor driven time element, and the purpose of this arrangement is to permit the traffic that was following the car, or held by the car stopping at the intersection, to have time to cross the intersection.

In the latter description only the control of an east-bound car was taken into consideration. 10 However, the control of the traffic signal will function similarly if a car moves westbound and operates relay R1 under the influence of trolley contactors 3W and 5W.

A further advantage accomplished in this system is that since the periodic timing of the indication is not interfered with, but only the circuits connecting the indications altered to provide a display of the W-E electric line green indication and the red N-S intersecting traffic 20 indication during that period of the cycle when the automatic timer would have provided a red indication for the E-W traffic and a green indication for the N-S traffic, any number of these traffic signal control units can be operated in 25 synchronism by having their motor driven time elements adjusted for the same total cycle time with their corresponding periods regulated accordingly.

In Fig. 2 the timing of a group of signals operating synchronously is graphically represented. 30 For simplicity the railway car and vehicular traffic are considered in one direction only, namely, eastbound. In the diagram, streets are arranged to intersect the electric railway at 880 35 feet intervals and the timing of the traffic signals located at each of the intersections is so arranged that all vehicles traveling at a speed equivalent to 20 M. P. H. can travel in a traffic lane thirty seconds wide and receive a green signal 40 indication at each intersection.

This system of synchronous traffic control is widely used at the present time and is known as the "wave" or "platoon" system. As it is well known to those versed in the art, a system so 45 timed for a certain speed will have several other lanes in which traffic may move at other speeds and always receive a green signal. These speeds are always less than the maximum arranged speed and in this instance are $6\frac{1}{2}$ miles per hour 50 and 4 miles per hour. For convenience, the sixty second line X, Y, of the graph has been calibrated in miles per hour, so that all lines intersecting this line extending from the zero point will indicate the relative speed represented 55 by that line. It can be readily seen from the graph that all vehicles moving at speeds other than the synchronous speeds will receive red signals at most of the intersections or all of them, depending upon the rate of speed at which 60 the vehicles move. This is very detrimental to the use of this type of signaling especially during the peak operating hours of the railway cars. During these peak hours the average speed of 65 the railway car is considerably reduced, and by reason of the varying loading time and speed, "traffic stagnation" of vehicles following the car usually results, and, as the car continues its course of travel through the signaled area, a considerable accumulation of the "bottled" 70 traffic in the rear of the car results.

In the graph the heavy dot-dash lines L represent a railway car starting at the beginning of the system traveling at a speed less than the maximum synchronous speed, thereby arriving 75 at the beginning of the red period at each suc-

cessive street intersection. At each of these intersections the railway car will be compelled to make a long objectionable stop and unnecessarily interfere with the progress of the vehicular traffic on that highway. From the latter it can readily be seen that if each of the signaled intersections were equipped with a relay system to control the display of the traffic signal indications, as heretofore described, the long objectionable stops would be eliminated, and the "bottled" traffic would be given a green signal to move on. This in effect is the same as opening an intermediate traffic lane in the system when a certain class of vehicles interfered with the synchronous speed travel of the system. On 15 the graph the medium dot-dash lines K indicate the travel of a railway car in an intermediate traffic lane produced by a relay system controlling the traffic signal indications in accordance with the movement of the car. It can be seen that a car starting at zero will move for the first block in a line corresponding with L and instead of receiving the ordinary red signal at the first intersection, the preceding green period at that intersection would be prolonged 20 by the passage of the current collector W1 of the car under the starting contactor 3E and a red indication removed as represented by the heavy dotted line in Fig. 2. The car then after making a loading stop is enabled to start immediately and clear the intersection on the prolonged 25 green period. If it continues at this same rate of speed, it will clear the second intersection within a normal green period and the normal operation of the traffic signal will not be interfered with. However, at the fourth intersection 30 it would have received a red indication, but with the use of the suitable control device at this location, the preceding green period would likewise be prolonged and the red indication removed as represented by the heavy dotted line in 35 Fig. 2 so that the car might also clear this intersection with the attendant advantages. It can be seen that the intermediate channel K can vary over wide limits and is governed entirely by 40 the speed of the car. For instance, if the car is traveling at a faster rate of speed, the lane will either coincide with the maximum traffic lane or neighbor it closely. Likewise if the car is moving at a much slower rate of speed, the 45 traffic lane will shift in the direction of the slower traffic lanes, and through these wide limits the street car will always establish an auxiliary traffic lane to suit the speed of the car. In addition to the saving of time for the railway 50 car which, by far, handles the greatest percentage of traffic, it relieves the traffic congestion that would have ordinarily occurred if the car were compelled to stop at each of the intersections. 55

It must be understood that at each of the intersections the conventional form of traffic signal is employed, using red, amber, and green signal indications, alternately displayed to the main and cross-thoroughfares. For simplicity only 60 the major indications red and green were considered and only the main line indications were described.

There are, of course, modifications and arrangements of the parts and circuits which may 65 be made from that shown in the above disclosure and which will still fall within the scope of our invention.

We claim:

1. In a traffic control system which comprises 75

a plurality of signal stations each station including a right of way indicating device and a constantly operating device therefor for normally cyclically shifting right of way from one thoroughfare to the other in synchronism with the operation of the remaining signal stations of the system; one of said signal stations including an electrically operated right of way indicating device for the main and cross thoroughfares at said station, a controller means driven by the constantly operating device at the signal station, circuit connections between said controller and the right of way indicating device; a traffic responsive means for said main thoroughfare having one condition of operation when traffic on said thoroughfare is approaching said intersection and is within a certain distance thereof, and a second condition of operation for all other positions of traffic on said thoroughfare with respect to said intersection, and relay means controlled jointly by the traffic responsive means and the controller means, and having contacts interposed in said circuits between said right of way indicating device and said controller for interrupting the normal cyclic display of the right of way indicating device and for constantly displaying right of way to said main thoroughfare when said traffic responsive means is in said first condition of operation and for restoring the cyclic control by the controller means when in said second condition.

2. In a traffic signaling device; an electrically operated right of way indicating device for main and cross thoroughfares; a constantly operating device; a controller means driven by the constantly operating device; circuit connections between said controller and the right of way indicating device, for normally cyclically shifting right of way from one thoroughfare to the other; a traffic responsive means for said main thoroughfare having one condition of operation when traffic on said thoroughfare is approaching said intersection and is within a certain distance thereof; and a second condition of operation for all other positions of traffic on said thoroughfare with respect to said intersection; and relay means controlled jointly by the traffic responsive means and the controller means and having contacts interposed in the circuits between the said right of way indicating device and the controller; for interrupting the normal cyclic display of the right of way indicating device and for constantly displaying right of way to said main thoroughfare when said traffic responsive means is in said first condition of operation and for restoring the normal cyclic control by the controller means when the traffic responsive means is in said second condition.

3. A traffic signaling system arranged at the intersection of a main highway and a crossroad for regulating traffic, said system including a highway signal lamp circuit and a crossroad signal lamp circuit, a time controlled switch means normally associated with the said circuits for alternately cyclically opening and closing same, relay means controlled by the said time switch means and by a vehicle on the main highway approaching the intersection, for maintaining the display of the said highway lamp, and means operable by the said vehicle after clearing the intersection to restore the periodic control of the said signals to the time controlled switch means.

4. A traffic signaling system arranged at the intersection of a main highway and a crossroad for regulating traffic, said system including a high-

way signal lamp circuit and a crossroad signal lamp circuit, a time controlled switch means associated with the said circuits for alternately cyclically opening and closing same, vehicular actuated means for the main highway operable to one position when a vehicle enters a certain zone with respect to the said intersection and a second position when the vehicle clears the said intersection, and relay means controlled jointly by the said vehicle means and time controlled switch means to interrupt the control of said circuits by the said time controlled switch means and to maintain the display of the said highway lamp for the main highway when the said vehicular actuated means is in the first mentioned position.

5. A traffic signaling system arranged at the intersection of a main highway and a crossroad for regulating traffic, said system including a highway signal lamp circuit and a cross road signal lamp circuit, a time controlled switch means normally associated with the said circuits for alternately cyclically opening and closing same, traffic responsive means actuated by a vehicle on the main highway approaching the intersection and upon clearing the said intersection, relay means having contacts interposed in the said lamp circuits, said relay means controlled jointly by the traffic responsive means and time controlled switch means to interrupt the control of said circuits by the said time controlled switch means and to maintain the display of the highway lamp when the said traffic responsive means is actuated by a vehicle approaching the said intersection and to restore the control to the said time controlled switch means when the said traffic responsive means is actuated by a vehicle clearing the intersection.

6. A right-of-way indicating device for interfering traffic lanes; a constantly operating device, a controller means driven by the constantly operating device; circuit connections between the said controller and right-of-way indicating device, for normally cyclically shifting right-of-way from one traffic lane to the other, other circuit connections to said right-of-way indicating device for a constant display of the right-of-way to one of the said traffic lanes, relay means activated by a vehicle, and means operable in response to actuation of said relay means when the right-of-way is displayed to said one lane for shifting from the first named circuit connections to the second named circuit connections whereby the normal cyclic display of the right-of-way is interrupted and the display of the right-of-way to the last mentioned traffic lane is maintained, and means affected by the vehicle for restoring the said relay means to normal whereby the normal cyclic display of the right-of-way is restored.

7. A traffic signaling system for regulating traffic on interfering traffic lanes, said system including a right-of-way indication for each of the said traffic lanes, a constantly operating device, and controller means driven by the said constantly operating device, circuit connections between the said controller and said right-of-way indications for normally cyclically shifting right-of-way from one traffic lane to the other, vehicle operated devices in one of said traffic lanes to be consecutively operated by a vehicle and, means affected by one of said devices when operated by a vehicle to interrupt the normal cyclic display of the said right-of-way indications and prolong the energization of the right-of-way indication

on the said one traffic lane a minimum time equal to one complete cycle, and to subsequently restore the normal cyclic control by the first said means when another one of the said devices is operated by the said vehicle.

8. A traffic signalling system arranged at the intersection of main and cross thoroughfares for regulating traffic, comprising a right-of-way indicating device and a time controlled switch means therefor, for normally cyclically shifting the right-of-way from one thoroughfare to the other, other means controlled jointly by the said time switch means and by a vehicle on the said main thoroughfare approaching the intersection, for maintaining the right-of-way on the last mentioned thoroughfare for a minimum total period equal to the total time of one complete cycle plus the time of its normal display, and means operable by the said vehicle after clearing the intersection to restore the normal cyclic control by the said time controlled switch means.

9. A traffic signaling system arranged at the intersection of main and cross thoroughfares for regulating traffic, comprising a right-of-way indicating device and a time controlled switch means therefor, for normally cyclically shifting the right-of-way from one thoroughfare to the other, other means controlled jointly by the said time switch means and by a vehicle on the said main thoroughfare, for maintaining the right-of-way on the last mentioned thoroughfare when the said vehicle is approaching the intersection a certain distance thereof, and to restore the normal cyclic control by the said time switch means after the vehicle clears the said intersection.

10. A traffic signaling system arranged at the intersection of main and cross thoroughfares for regulating traffic, said system comprising a right-of-way indicating device and a time controlled switch means therefor for normally cyclically shifting the right-of-way from one thoroughfare to the other, traffic responsive means actuated by a vehicle on the main thoroughfare approaching the said intersection and restored to a normal condition by the said vehicle upon clearing the intersection, and means controlled by the said time controlled switch means to maintain the right-of-way on the last mentioned lane when the said traffic responsive means is actuated by a vehicle approaching the intersection and to restore the normal control of the right-of-way indicating device to the said time controlled switch means only after the said traffic responsive means is restored to a normal condition by a vehicle clearing the intersection.

11. A traffic signaling system for interfering traffic lanes, said system comprising a right-of-way indicating device and a time controlled switch means therefor for normally cyclically shifting the right-of-way from one traffic lane to the other, other means controlled by the said time switch means and by a vehicle on one of the said traffic lanes for maintaining the right-of-way on the last mentioned traffic lane for a minimum total period equal to a normal display of the right-of-way to said one lane increased by the total time of one complete cycle.

12. In a traffic system for intersecting streets, a right-of-way indication, means displaying said indication to each of said streets for predetermined times for the control of traffic, a vehicle responsive device for one of the said streets and a second means operable upon an actuation of said device for cooperating with the first named means to extend the time of display of said in-

dication to the last mentioned street beyond the time determined by the first named means, said second means to further extend the time of display of said indication upon subsequent actuations of the said device occurring within predetermined intervals of each other.

13. In a traffic system for interfering lanes, a right-of-way indication; means cyclically displaying said indication normally to each of said lanes for predetermined times for the control of traffic; a vehicle-actuated device in one of said lanes; and means, operating in response to an actuation of the said device, and cooperating with the first named means when the right-of-way is displaying to the said one lane, for extending the time of display of the said indication to the said one lane for a period of time equal to the normal time of one complete cycle.

14. A traffic control system for intersecting traffic lanes having right-of-way traffic signals for each lane, and circuits for energizing the same; an electric motor operating at a predetermined time rate, and a shaft and switches operated thereby for energizing said signal circuits through continuous successive cycles, in each of which cycles the right-of-way signals for the lanes are energized alternately for predetermined periods of time; means responsive to traffic in one of said lanes; relay means operatively associated with the circuits of the right-of-way signals for the other of said lanes and the corresponding motor-operated switches for controlling connection of the latter, said relay means having a normally de-energized condition for connecting the latter said circuits to the said corresponding switches, and an energized condition for disconnecting the latter circuits from said corresponding switches; an auxiliary circuit for energizing directly the right-of-way signals for the said one lane, including a switch closed by the said relay means in its energized condition; an operating circuit for the said relay means connected with said traffic responsive means, and including a switch closed by the said shaft in the right-of-way period for the said one lane, for energizing said relay means during said latter period in response to traffic in the said one lane; and a holding circuit for the said relay means, including a switch closed by the said shaft at the end of the right-of-way period for the said one lane, which switch is retained closed by the said shaft until the beginning of the following right-of-way period for the said one lane for retaining the said relay means energized through the cycle until the beginning of the said following right-of-way period for the said one lane.

15. A traffic control system for intersecting traffic lanes having right-of-way signals for each lane, and circuits for energizing the same; an electric motor operating at a predetermined time rate, and a shaft and switches operated thereby for energizing said circuits through continuous successive cycles, in each of which cycles the right-of-way signals for the lanes are energized alternately for predetermined periods of time; traffic responsive means for one of said lanes having one condition of operation when traffic on the said one lane is approaching the said intersection and is within a certain distance thereof, and a second condition of operation for all other positions of traffic on the said one lane with respect to the said intersection; relay means operatively associated with the circuits of the right-of-way signals for the other of said lanes and the corresponding motor-operated switches

for controlling connection of the latter, said relay means having a normally de-energized condition for connecting the latter said circuits to the said corresponding switches, and an energized condition for disconnecting said latter circuits from said corresponding switches; an auxiliary circuit for energizing directly the right-of-way signals for the said one lane, including a switch closed by the said relay means in its energized condition; an operating circuit for the said relay means, including a switch closed by the traffic responsive means in its said one condition of operation and a switch closed by the said shaft for the duration of the right-of-way period for the 10 said one lane, for energizing said relay during said latter period; and a holding circuit for the said relay means, including a switch closed by the relay means in its energized condition and a switch closed by the shaft at the end of the 15 right-of-way period for the said one lane, which switch is retained closed by the said shaft until the beginning of the following right-of-way period for the said one lane for retaining the said relay means energized through the cycle until the 20 beginning of the said following right-of-way period for the said one lane.

16. A traffic control system for intersecting traffic lanes having right-of-way signals for each lane, and circuits for energizing the same; an 30 electric motor operating at a predetermined time rate, and a shaft and switches operated thereby for energizing said circuits through continuous successive cycles, in each of which cycles the right-of-way signals for the lanes are energized alternately for predetermined periods of time; control means responsive to traffic in one of said lanes; relay means operatively associated with the circuits of the right-of-way signals for the other of said lanes and the corresponding 35 motor-operated switches for controlling connection of the latter, said relay means having a normally de-energized condition for connecting the latter said circuits to said corresponding switches, and an energized condition for disconnecting said latter circuits from said corresponding switches; an auxiliary circuit for energizing directly the right-of-way signals for the said one lane including a switch closed by the said relay means in its energized condition; an operating 40 circuit for the said relay means, including a switch closed by the traffic responsive means in its said one condition of operation and a switch closed by the said shaft in the right-of-way period for the said one lane for energizing said relay during said latter period; a stick circuit for maintaining said relay means energized, including a switch closed by the relay means in its energized condition and a switch closed by the traffic responsive means in its said one condition of operation; and a holding circuit for retaining the said relay means energized through the cycle 45 until the beginning of the said following right-of-way period for the said one lane when the traffic responsive means is restored into its second condition of operation during the periods in which the circuits of the right-of-way signals 50 for the said other lanes are energized, including a switch closed by the said relay means in its energized condition, and a switch closed by the shaft at the end of the right-of-way period for the said one lane, which switch is retained closed 55 by the said shaft until the beginning of the said following right-of-way period for the said one lane.

SAMUEL S. STOLP.

FRANK H. RICHTERKESSING. 60

period for the said one lane for retaining the said relay means energized through the cycle until the beginning of the said following right-of-way period for the said one lane.

17. A traffic control system for intersecting traffic lanes having right-of-way traffic signals for each lane, and circuits for energizing the same; an electric motor operating at a predetermined time rate, and a shaft and switches operated thereby for energizing said signal circuits through continuous successive cycles, in each of which cycles the right-of-way signals for the lanes are energized alternately for predetermined periods of time; traffic responsive means for one of said lanes having one condition of operation when traffic on the said one lane is approaching the said intersection and is within a certain distance thereof, and a second condition of operation for all other positions of traffic on the said one lane with respect to the said intersection; relay means operatively associated with the circuits of the right-of-way signals for the other of said lanes and the corresponding motor-operated switches for controlling connection of the latter, said relay means having a normally de-energized condition for connecting the latter said circuits to the said corresponding switches, and an energized condition for disconnecting said latter circuits from said corresponding switches; an auxiliary circuit for energizing directly the right-of-way signals for the said one lane, including a switch closed by the said relay means in its energized condition; an operating circuit for the said relay means, including a switch closed by the traffic responsive means in its said one condition of operation and a switch closed by the said shaft in the right-of-way period for the said one lane for energizing said relay during said latter period; a stick circuit for maintaining said relay means energized, including a switch closed by the relay means in its energized condition and a switch closed by the traffic responsive means in its said one condition of operation; and a holding circuit for retaining the said relay means energized through the cycle 45 until the beginning of the said following right-of-way period for the said one lane when the traffic responsive means is restored into its second condition of operation during the periods in which the circuits of the right-of-way signals 50 for the said other lanes are energized, including a switch closed by the said relay means in its energized condition, and a switch closed by the shaft at the end of the right-of-way period for the said one lane, which switch is retained closed 55 by the said shaft until the beginning of the said following right-of-way period for the said one lane.
